UNITED STATES PATENT OFFICE.

EDWARD E. MURPHY, JR., OF TOTTENVILLE, NEW YORK.

LIQUEFIED ANÆSTHETIC.

SPECIFICATION forming part of Letters Patent No. 275,511, dated April 10, 1883.

Application filed January 15, 1883. (No specimens.)

To all whom it may concern:

Be it known that I, EDWARD E. MURPHY, Jr., of Tottenville, in the county of Richmond and State of New York, have invented a new and Improved Etherized Nitrous-Oxide Gas, 5 of which the following is a full, clear, and exact description.

Nitrous oxide, generally known as "laughing-gas," is commonly administered by dentists 10 to produce anæsthesia, for the purpose of permitting dental operations to be performed without paining the patient. The effect of the nitrous oxide—that is, the anæsthesia produced by the gas—very frequently disappears 15 before the operation is completed, and thus causes much discomfort to the patient and annoyance to the operator.

The object of my invention is to improve the 20 anæsthetic properties of the gas in such a manner that the anæsthesia produced will be of longer duration. To this end I saturate the nitrous oxide with sulphuric ether in a manner that will be fully set forth and described hereinafter.

25 Reference is to be had to the accompanying drawing, forming part of this specification, in which the apparatus which I use for saturating the nitrous oxide with sulphuric ether is shown, parts being in section.

30 The nitrous oxide is produced in the usual manner, and when in a perfectly-pure state it is conducted through the pipe A into the gasometer B, of the usual construction. From the said gasometer it passes through the outlet-pipe C into a cylindrical vessel, D, and from the same to a compressing-pump, E, in which it is liquefied by subjecting it to a pressure of from seven hundred to eight hundred pounds per square inch. In the liquefied state it is 35 contained in closed wrought-iron vessels, in which it is sold to the consumers. As soon as the liquid gas is drawn from the said vessel

and liberated it expands and assumes the gaseous form again. A series of transverse partitions, F, are formed of some fabric within the 45 cylindrical vessel D, and a sufficient quantity of sulphuric ether is poured into the said vessel D to cause the lower parts of the said fabric partitions to be immersed in sulphuric ether. By the capillary attraction the sulphuric ether is distributed over the entire surface of the fibrous partitions, and as the nitrous oxide passes through the vessel D it must pass through the partitions F saturated with liquid sulphuric ether. Thereby the nitrous oxide 50 becomes saturated with sulphuric ether, and in that state passes to the pump E and is compressed. When saturated the nitrous oxide 55 contains about from five to six per cent. of sulphuric ether. The etherized nitrous oxide thus produced causes anæsthesia much more rapidly than the ordinary nitrous oxide, and the anæsthesia is of considerably longer duration. The etherized nitrous oxide is perfectly 60 harmless, if properly administered.

Having thus described my invention, what I 65 claim as new, and desire to secure by Letters Patent, is—

1. The process of forming a permanently-compressed portable liquid compound of sulphuric ether and nitrous oxide, which consists in forcing nitrous-oxide gas through fabric saturated with sulphuric-ether liquid and then compressing the mixture into a liquid form, as 70 described.

2. The product of the above-described process, being a permanently-compressed portable liquid compound of nitrous oxide and sulphuric ether, substantially as described.

EDWARD E. MURPHY, JR.
